UNITED STATES PATENT OFFICE.

JOHN WATERSTRAW, OF FARMINGTON, NEW YORK.

TOY.

SPECIFICATION forming part of Letters Patent No. 361,735, dated April 26, 1887.

Application filed January 17, 1887. Serial No. 224,567. (No model.)

To all whom it may concern:

Be it known that I, JOHN WATERSTRAW, of the village of Farmington, in the county of Ontario and State of New York, have invented 5 a new and useful Improvement in Toys, which improvement is fully set forth in the following specification and shown in the accompanying drawings.

The object of my invention is to produce a 10 rolling and revolving toy, the same being hereinafter fully described, and more particularly pointed out in the claims.

Referring to the drawing, Figure 1 is a side elevation of my improved toy, the tongue and 15 turret being in part broken away, and the latter in part vertically and centrally sectioned, as upon the dotted line *y* in Fig. 2, the figure being viewed as indicated by arrow *z*; Fig. 2, a plan of the same; Fig. 3, a side elevation of 20 the driving-wheel and other parts drawn in outline, drawn to show more fully the manner of hanging the driving-wheel, parts being shown in various positions by full and dotted lines, and the axial pin of the driving-wheel 25 transversely sectioned, the figure being seen in the direction in which Fig. 1 is seen; and Fig. 4, a detached view more fully showing the relation of the turret and the standard upon which it turns.

Referring to the parts, *A* is the body of the 30 toy, mounted upon carrying-wheels *B*, similar to the manner in which a wagon is mounted upon its wheels.

C is the turret fitted to turn upon a post or 35 standard, *b*, rising perpendicularly from the middle point of the body and made rigid therewith.

d is the driving-wheel for the turret, preferably placed in a longitudinal opening, *a*, in 40 the body, at one side thereof, in position to have its periphery bear against the under surface of the turret, near the periphery thereof, as shown. The driving-wheel turns upon a pin, *f*, which occupies a vertically-elongated 45 cavity, *h*, in the body, crossing the opening *a*.

The driving-wheel is provided with an india-rubber tire, *c*, to increase its hold upon the floor and the turret, the surface of the latter, against which the driving-wheel bears, being 50 covered with a ring, *e*, of india-rubber or other

rough material, to increase the friction between said driving-wheel and turret. The driving-wheel is of the same diameter as the carrying-wheels, and as the axes of all these wheels are in the same plane, the driving-wheel will, under ordinary circumstances, bear upon the floor and be turned in the direction indicated by arrow as the toy is moved along; and as the turret rests upon the driving-wheel, it will be turned by the latter in a horizontal plane in 60 the direction indicated.

The turret is designed to hold a series of figures, *g*, representing men, animals, birds, or other things to amuse children, the same being carried around as the toy is drawn along the 65 floor.

On account of the axial pin *f* of the driving-wheel occupying openings *h*, vertically elongated, the driving-wheel is permitted a certain amount of vertical motion independent of the 70 body, so that it will rise over obstacles or drop into depressions in the floor as the toy is carried along. On account of this the driving-wheel will pass over the inequalities in the floor and always be in contact therewith, and 75 not cease to rotate while the toy is moving.

The turret is provided with a vertical motion upon the standard *b*, so that it will easily rise and fall with the driving-wheel and remain constantly in contact therewith, and be 80 turned, as stated, whenever said driving-wheel is turned upon its axis. The pin *f* is made rigid in the driving-wheel, and turns with the latter in the body.

A toy having a body mounted upon the axle 85 of carrying-wheels and caused to turn upon a spindle from bearing against a disk rigid with said wheels or axle, said disk being independent of the floor, is not new, and I do not claim such construction, broadly.

What I claim as my invention is—

1. A toy consisting of a body mounted upon carrying-wheels, said body being provided with a driving-wheel bearing against the floor, in combination with a turret or disk held to 90 turn upon a rigid spindle projecting from said body in position to bear against said driving-wheel to be turned thereby, the latter being provided with an india-rubber tire or peripheral band, and the turret provided with a cov- 95

ering of rough material where it is touched by said driving-wheel, substantially as shown and described.

2. A body of a toy mounted upon carrying-wheels, in combination with a driving-wheel having its axial pin occupying elongated openings in said body, a turret held in position to bear upon said driving-wheel, and a standard for said turret projecting from said body, substantially as and for the purpose specified.

3. A body of a toy mounted upon carrying-wheels, a driving-wheel having its axial pin

occupying vertically-elongated openings in said body, in combination with a turret over said driving-wheel and in position to bear thereon, and a holder for said turret, the latter having a motion upon said holder toward or from said driving-wheel, substantially as and for the purpose set forth. 15

JOHN WATERSTRAW.
